SAMUEL L. ROMANO, OF VANCOUVER, BRITISH COLUMBIA, CANADA.

FORMING-MOLD FOR SEWER-CONDUITS.

1,143,862.

Specification of Letters Patent. Patented June 22, 1915.

Application filed January 26, 1914. Serial No. 814,482.

To all whom it may concern:

Be it known that I, SAMUEL L. ROMANO, a citizen of the Dominion of Canada, residing at Vancouver, in the Province of British Columbia, Canada, have invented certain new and useful Improvements in Forming-Molds for Sewer-Conduits, of which the following is a specification.

This invention relates to a forming mold for the construction of large sized sewers or the like in concrete.

The primary object of the invention is to provide mold plates on which the concrete may be formed, which mold plates are supported from within in a manner that they are retractable from the concrete when it is set, and being mounted on a wheeled truck may be run forward and expanded again to the required size for the next length to be molded on it.

In an amplification of the idea retracting means is such as to enable the form to be used for considerable variations of size and form the mold plates being changed in their relation to one another and to the adjusting means.

The invention is particularly described in the following specification, reference being made to the drawings by which it is accompanied, in which:

Figure 1 is a cross section showing the several form plates in their extended position for a conduit of circular cross section. Fig. 2 shows the same as with the crown plates removed for forming a sewer of substantially ovoid section. Fig. 3 is a side elevation of the form carrying frame as set forth in Fig. 1, the form plates on one side removed to show the support. Fig. 4 is an end elevation of the part of the invention in the first stages of its use. Figs. 5 and 6 are detail views of portions of the invention.

In these drawings 2 represents the base or lower segment of a concrete sewer of circular cross section, the circular arc of its upper surface having been straked or swept to the required form by means of mold boards or a templet. On this lower segment 2 track rails 3 are laid on which the portable frame, which carries the form plates, may be moved forward as the work requires. This form plate carrying frame 4 is of a length corresponding to the length of each section which may be convenient and is preferably made of plate metal bent to a substantially triangular cross section somewhat as shown.

To the underside of this frame 4 the axles 5 of the carrying wheels 6 are secured, one being adjacent to each end of the frame and one in the middle, and over each pair of 60 wheels attachments 8 and 9 are secured on each side to the frame 4, to which attachments are connected the form plate sustaining and adjusting means.

The form plates are preferably made of 65 sheet metal, but may be of wood if found more convenient. They comprise a lower and upper side plate 20 and 21 on each side, and four narrow crown plates 22, each having a rib 23, 24 and 25 of light channel or 70 rail section opposite to each connection to the carrying frame. The ribs 23 and 24 are pin-connected together at 26 the hinge pin being removable.

The side plates 20 and 21 are adjustably 75 connected to the attachments 8 and 9 of the frame 4 in the following manner: On each projecting attachment 8 and 9, which extend relatively horizontally outward and angularly upward from the frame 4, are welded or otherwise secured tubular supports 10 and 11. These extend toward the lower edge of the lower side plates 20 in the case of the former, and toward the middle of the upper side plates 21. To the ribs 23 and 24 of 80 these side plates are pin-connected at 16 and 17, the ends of screws 12 and 13, the other ends of which screws pass into and are adjustable in the tubes 10 and 11 by means of a cross handled nut 14 or 15 threaded on each 90 screw and bearing on the end of each tube. The narrow crown plates 22 are supported from the upper edges of the side plates 21 on each side, the edges of the plates being half-lapped, and the ribs 25 having members 95 27 secured in their channels which members project beyond the width of the plate, as shown in Fig. 5 of the drawing, to enter into the channels of the ribs of the adjacent plate.

With this construction of form plate support, the lower or base segment 2 of the sewer having been poured and the concrete set the track rails 3 are laid upon it, and the carrying frame 4 with the upper side 105 form plates removed and the lower side plates retracted, is run into position on it. The lower side plates are by means of the nuts screwed out to their desired extension, as shown in Fig. 4, and struts 30 are introduced between the upper edge of the lower side plates 20 and a pin-connecting lug on 110

the upper end of each tube 11, and also struts 31 between lugs provided on the upper end of each screw 13. On these cross struts 31 light tracks may be laid for the delivery of concrete to the workers, and the concrete may be tamped from within the side plates as delivered.

When the concrete has been poured to the approximate level of the upper edge of the lower side plates 20 the struts 31 are removed and the nuts 15 are rotated to advance the screws 13 toward the upper limit of their movement. The upper side plates 21 are then pin-connected at 26 to the lower plate 20 and to the heads of these screws 13, and after extension to their required position, a cross strut 32 is introduced between the upper ends of these screws 13. On the struts 32 a light track may be carried to convey the concrete forward to the workers. The concrete is then poured and tamped around the upper side form plates 21, and the crown plates 22 are introduced to sustain the concrete for the crowning section of the sewer. After the concrete is set, the tracks and cross struts 30, 31 and 32 and crown plates 22 are removed, the side plates 20 and 21 are retracted by means of the nuts 14, and 15, and the entire frame is moved forward for the next length of the sewer conduit.

Where a conduit of substantially ovoid form is required, the same can be formed by removing the crown plates 22 and bringing the upper edges of the upper side plates 21 together, as shown in Fig. 2.

The same manner of supporting and retracting the form plates can be used for form plates bent to different shapes to construct a conduit of any desired form of cross section or size.

Provision for carrying the concrete within the form frame to the work will not be required unless the same is being conducted in a tunnel.

Where the conduit is being made in an open cut it will be more conveniently delivered from above.

A simple and convenient device is thus provided by which such work as it has been designed for can be more economically and quickly conducted.

It will be observed that the ends of the screws 12-13 are susceptible of adjustment by having their pivotal connections 16-17 respectively changed to any one of a series of pin holes, as shown in Figs. 1 and 2 of the drawings.

Having now particularly described my invention, I hereby declare that what I claim as new and desire to be protected in by Letters Patent, is:

1. A form supporting frame for conduit construction in concrete, comprising the combination with a wheeled truck of screw

jacks immovably secured to the truck, said jacks pin-connected to the lower edges of lower side form plates and to approximately the mid-width of upper side form plates, and means for removably connecting together the edges of said lower and upper side plates.

2. A form supporting frame for conduit construction in concrete, comprising the combination with a wheeled truck of tubes immovably secured to and projecting laterally outward horizontally and angularly upward from the truck on each side, a screw endwise movable within each tube, said screws connected at the outer ends to the form plates, and a nut threaded on each screw and bearing on the ends of its tubular support.

3. A form supporting frame for conduit construction in concrete, comprising the combination with a wheeled truck of tubular supports rigidly secured to the truck and projecting laterally outward horizontally and angularly upward on each side from the truck, a screw endwise movable in each tubular support, said screws connected to lower and upper side form plates the adjacent edges of which are hinge connected together, a nut threaded on each screw and bearing on the end of its tubular support, and narrow crown plates supported on the upper edges of the upper side plates.

4. In an apparatus of the character stated, a wheeled truck including a truck frame, two sets of screw jacks, each having one of their ends rigidly secured to the truck frame, one set of jacks extending in a horizontal plane from each side of the truck frame, the other set of jacks extending upwardly and divergently from each side of the truck frame, and form plates supported by said jacks.

5. In an apparatus of the character stated, a wheeled truck including a truck frame, two sets of screw jacks, each having one of their ends rigidly secured to the truck frame, one set of jacks extending in a horizontal plane from each side of the truck frame, the other set of jacks extending upwardly and divergently from each side of the truck frame, form plates supported by said jacks, said form plates including a pair of lower plate sections, to the lower edges of which the horizontal jacks are connected, a pair of upper form plates, means connecting the adjacent edges of said upper form plates together at the top of the form, means pivotally connecting the lower edges of said upper form plates to the upper edges of said lower form plates, said upwardly projecting set of jacks being secured to said upper form plates at locations approximately midway between the upper and lower edges of the same, substantially as shown and described.

6. In an apparatus of the character stated,

a wheeled truck including a truck frame, two sets of screw jacks, each having one of their ends rigidly secured to the truck frame, one set of jacks extending in a horizontal 5 plane from each side of the truck frame, the other set of jacks extending upwardly and divergently from each side of the truck frame, form plates supported by said jacks, said form plates including a pair of lower 10 plate sections, to the lower edges of which the horizontal jacks are connected, a pair of upper form plates, means connecting the adjacent edges of said upper form plates together at the top of the form, means pivotally connecting the lower edges of said upper form plates to the upper edges of 15 said lower form plates, said upwardly projecting jacks being secured to said upper form plates at locations approximately midway 20 between the upper and lower edges of the same, and cross struts connecting the upper ends of said upwardly extended jacks.

7. In an apparatus of the character stated, a wheeled truck including a truck frame, 25 two sets of screw jacks, each having one of their ends rigidly secured to the truck frame, one set of jacks extending in a horizontal plane from each side of the truck frame, the other set of jacks extending upwardly and 30 divergently from each side of the truck frame, form plates supported by said jacks, said form plates including a pair of lower plate sections, to the lower edges of which the horizontal jacks are connected, a pair 35 of upper form plates, means connecting the adjacent edges of said upper form plates together at the top of the form, means pivotally connecting the lower edges of said

upper form plates to the upper edges of said lower form plates, said upwardly projecting 40 set of jacks being secured to said upper form plates at locations approximately midway between the upper and lower edges of the same, cross struts connecting the upper ends of said upwardly extended jacks, and a 45 trackway mounted on said cross struts.

8. A jack form comprising a wheeled truck having a frame, two sets of screw jacks each comprising a supporting tube, a screw and an abutment nut, said screws adapted 50 to project into the respective tubes and said nuts adapted to abut the same, means for rigidly securing said tubes to the truck frame in two sets, one set of tubes extending in a horizontal plane to each side of the 55 truck frame, and the other set extending upwardly and divergently from each side of the truck frame, two sets of form plates; one set of form plates comprising a lower form section to the lower extremities of 60 which the horizontal jack screws are pivotally connected, the other set of form plates comprising a pair of plates secured together at their upper ends and having their lower extremities pivotally secured to the upper 65 extremities of said lower form plates, the jack screws of said upwardly projecting jacks being pivotally secured to said upper form plates substantially as shown and described. 70

In testimony whereof I affix my signature in presence of two witnesses.

SAMUEL L. ROMANO.
